UNITED STATES PATENT OFFICE.

HARLEY J. EARL, OF DETROIT, MICHIGAN, ASSIGNOR TO GENERAL MOTORS CORPORATION, OF DETROIT, MICHIGAN, A CORPORATION OF DELAWARE.

DESIGN FOR A RADIATOR.

Application filed August 18, 1928. Serial No. 27,884. Term of patent 14 years.

To all whom it may concern:

Be it known that I, HARLEY J. EARL, citizen of the United States, and resident of Detroit, county of Wayne, State of Michigan, have invented a new, original, and ornamental Design for Radiator, of which the following is a specification, reference being made to the accompanying drawing, forming a part thereof.

In the drawing:

Figure 1 is a front view;

Figure 2 is a plan view of my new design for radiator.

I claim:

The ornamental design for a radiator as shown.

HARLEY J. EARL.
